REUBEN BRADY, OF NEW YORK, N. Y.

Letters Patent No. 98,550, dated January 4, 1870.

IMPROVEMENT IN MACHINE FOR CUTTING AND PRESSING THE HEADS OF METAL CANS

The Schedule referred to in these Letters Patent and making part of the same.

To all whom it may concern:

Be it known that I, REUBEN BRADY, of the city, county, and State of New York, have invented a new and improved Machine for Cutting and Pressing the Heads of Metal Cans; and I do hereby declare that the following is a full, clear, and exact description thereof, which will enable others skilled in the art to make and use the same, reference being had to the accompanying drawings, forming part of this specification, in which—

Figure 1 represents a front elevation, partly in section, of my improved cutting and pressing-machine.

Figure 2 is a side elevation of the same.

Figure 3 is a sectional diagram of the head, as cut and pressed.

Similar letters of reference indicate corresponding parts.

This invention relates to a new machine for cutting from large plates the circular heads or end-pieces of sheet-metal cans, and for, at the same time, forming the flanges on the same, both operations being performed by one single motion of the main working-lever.

The invention consists chiefly in the employment of a hollow cutter, and of a punch or presser sliding thereon, the presser being operated by a rocking lever, which, during part of its motion, also carries along and moves the cutter.

A, in the drawing, represents the frame of my improved machine.

On it are formed two parallel guides, *a a*, for a vertical slide, B, which, at its lower end, carries an annular cutter, C.

The slide B is, by links *b b*, connected with a lever, D, which is pivoted to the frame A, and weighted, at its rear end, to hold the cutter elevated above the cutting-bed or die E.

Through the slide B is fitted a vertical rod, *c*, which carries, at its lower end and within the hollow cutter C, a block or punch, F.

The upper end of the rod *c* is, by links *d d*, connected with a lever, G, that is pivoted to the frame A, above the lever D.

The rear end of the lever G extends further back than that of D.

H is a bar, pivoted, near its upper end, to the back part of the lever G, the upper end being drawn forward by a spring, *e*.

A catch or shoulder, *f*, is formed on the lever H. When both the cutter and the punch are drawn up, the rear ends of the levers D G are lowered, and the catch *f* fits under the back end of the lever D.

When the machine is to operate, a plate of sheet-metal is placed upon the die, and then the rear end of the lever G is swung up, the catch *f* drawing the lever D along. The latter motion will cause the cutter to descend toward and cut out of the plate on the die a circular piece.

As soon as the cutter has performed its work, the catch *f* slips off the lever D, and the latter, by the weight on its rear end, draws the cutter up out of the way.

The lever G, in the mean time, continues to move, and serves gradually to force the presser upon the circular piece cut out by the cutter, and to turn up the edge *g* of the same, as in fig. 3.

Thus, by one motion of the lever G, both the cutting and pressing-operations are performed.

Having thus described my invention,

I claim as new, and desire to secure by Letters Patent—

1. The lever D, holding the annular cutter, in combination with the bar H and lever G, which holds the internal presser F, all arranged to operate as set forth.

2. The levers D G, so arranged that they will be automatically connected and disconnected during their motion, as specified.

3. The bar H and catch *f*, arranged to arrest the cutting-lever, while the punching-lever remains in action, as set forth.

REUBEN BRADY.
